UNITED STATES PATENT OFFICE.

GEORGE H. REYNOLDS, OF NEW YORK, N. Y., ASSIGNOR, BY DIRECT AND MESNE ASSIGNMENTS, TO THE CRANE ELEVATOR COMPANY, OF CHICAGO, ILLINOIS.

ELECTRIC VALVE-OPERATING MECHANISM FOR ELEVATORS.

SPECIFICATION forming part of Letters Patent No. 361,778, dated April 26, 1887.

Application filed November 23, 1886. Serial No. 219,583. (No model.)

To all whom it may concern:

Be it known that I, GEORGE H. REYNOLDS, of the city and county of New York, in the State of New York, have invented a new and useful Improvement in Valve-Operating Mechanism for Elevators, of which the following is a specification.

According to the most improved plans now in use, the main valve whereby motive fluid is admitted to and exhausted from the operating-cylinder of a hydraulic or other elevator is itself operated by a controlling-piston and cylinder, which constitute an independent motor-piston for the purpose, and the said motor-piston is controlled in its operation by an auxiliary valve or pilot-valve which is moved by appliances from the car. According to the method at present in use, the auxiliary or pilot valve is operated by a handle or lever on the car, which is by suitable means so connected with the auxiliary or pilot valve that a movement of the said lever or handle by the attendant in the car will produce a corresponding movement of the auxiliary or pilot valve. The auxiliary or pilot valve above referred to does not require any great power to operate it; and my present invention relates to novel combinations of mechanism whereby an electric circuit through which the current is controlled by a circuit-closing device to be operated by the attendant on the car is substituted for the positive mechanical connections which have heretofore served as a means of transmitting movement to the valve from the handle or lever of the car.

The valve, which is primarily operated from the car to produce the operation of the main valve and its motor, may consist simply of an auxiliary valve, which is unconnected with the main valve and its motor-piston and which is operated entirely independent thereof, or such auxiliary valve may have such suitable connections with the main valve and its operating motor-piston that during the movement of the main valve and its operating motor-piston the auxiliary valve will also be operated simultaneously therewith, and when the auxiliary valve is thus combined with the main valve and its operating motor I term it a

"pilot-valve". Such a pilot-valve is illustrated and fully described in my Letters Patent No. 314,720, granted March 31, 1885.

In carrying out my invention I employ an electric motor of simple construction which is mechanically connected with the auxiliary or pilot valve, and I provide a switch or circuit-closing device to be operated by the attendant on the car, and which, together with the electric motor, is included in the electric circuit. The electric motor may consist simply of an armature-lever having an arm connected with the auxiliary valve and two electric magnets arranged on opposite sides of the fulcrum of said lever, whereby the armature-lever may be tilted in one direction or the other to operate the valve and springs or analogous balancing devices, whereby the armature-lever and the valve, when the circuit is broken, will be moved to a central or neutral position for holding the main valve and its operating-motor inoperative.

The invention consists in novel combinations of parts, above referred to and particularly hereinafter described, and pointed out in the claims, whereby the desired results are attained.

In the accompanying drawings, Figure 1 is sectional elevation of an elevator car or cage operating within a well or shaft, together with a valve and portion of the operating-cylinder and an electric motor connected for operation according to my invention, the auxiliary valve being shown in mid-position, so as to hold the main valve and its operating-motor inoperative. Fig. 2 is a sectional elevation, upon a larger scale, of the valve apparatus, showing the auxiliary valve shifted so as to produce the movement of the main valve and its operating-motor in a direction to permit the exhaust of motive fluid from the main operating-cylinder and the descent of the car. Fig. 3 is a view corresponding to Fig. 2, but showing the auxiliary valve as shifted to produce the operation of the main valve and its controlling-piston in a direction to admit motive fluid to the main operating-cylinder in order to produce the ascent of the car. Fig. 4 is a transverse section on the plane of the

dotted line x x , Fig. 2. Fig. 5 is an elevation of the electric motor upon a larger scale than Fig. 1. Figs. 6 and 7 are a face view and a vertical section, upon a larger scale than Fig. 5, 1, of a very desirable construction of switch or circuit-closing device to be arranged in the elevator-car. Fig. 8 is an elevation of a portion of a car and the valve apparatus which is controlled by electricity from the car, and 10 which includes an auxiliary valve so connected with the main valve and its operating-motor as to be moved simultaneously therewith, and which I have therefore termed a "pilot-valve." Fig. 9 is a plan of the electric motor shown in Fig. 8 for shifting the pilot-valve, and Fig. 15 10 is a horizontal section of a portion of the car and a circuit-closing device or switch of modified form.

Similar letters of reference designate corresponding parts in all the figures.

Referring first to Figs. 1 to 7, inclusive, A designates the elevator-car, which may be suspended from cables in a well-known manner, and which rises and falls within the elevator- 25 shaft B.

C designates a portion of the main operating-cylinder, and C' the piston, which is movable therein to produce the rising or falling of the elevator-car A in a well-understood 30 manner. The valve apparatus which is employed to control the flow of motive fluid to the main operating-cylinder C and its exit therefrom may be of any suitable character so long as it comprises a main valve, a motor- 35 piston or controlling-piston connected therewith for operating it, and an auxiliary or pilot valve which is shifted through an electric circuit from the car A in order to control the operation of the main valve and its controlling 40 or motor piston.

In the valve apparatus which I have illustrated by way of example, there is a main valve cylinder or easing, D, in which are fitted two pistons, D' D², connected by a rod, D³; 45 and this cylinder D has at one end an extension or cylinder, D⁴, of smaller size, to which is fitted a piston, D⁵. These pistons may have any suitable packing. From the valve-cylinder D an inlet-passage, c, leads to the main operating-cylinder C, and an exhaust-passage, c', leads to the sewer or other point of delivery of the water. With the cylinder D is connected a main inlet-pipe, d, for motive fluid under pressure, and the cylinder is surmounted by an auxiliary valve-chest, E, in which an auxiliary valve, E', is arranged for operation. 50 From the main inlet-pipe d a branch pipe, d', admits motive fluid under pressure to the auxiliary valve-chest E. From the auxiliary valve-chest E two passages, d² d³, lead to the main valve-cylinder D, and the auxiliary valve E' may be operated by a rock-shaft, e, having within the chest an arm, e', engaging the valve E', and outside the chest a second arm, e², with 55 which is connected a rod, e³.

It will be understood that the piston D⁵ is considerably smaller in diameter than the pis-

tons D' D², and for the purpose of illustration we will suppose that it is half the area of the pistons D' D².

The pistons D² D⁵ may be termed "controlling" or "motor" pistons, on which the pressure of fluid acts to move the main valve D', and as said main valve is also aided in its movement in one direction by pressure upon it, it 75 therefore may be considered as forming a part of the motor.

It will be understood that the water or fluid under pressure entering from the pipe d acts upon the pistons D' D⁵, in opposite directions, 80 while the pressures upon the pistons D' D² will balance each other.

In the position of parts shown in Fig. 1, the auxiliary valve E' is set so as to close both ports d² d³, and the valve-piston D', being immediately over the passage c, closes it, and, as no water can enter or leave the main operating-cylinder C, the mechanism is idle or is 85 inoperative. Suppose, for example, that it be desired to admit motive fluid to the main cylinder C in order to move the piston C' in the direction of the arrow shown in Fig. 1, and thereby produce the rising movement of the car. The auxiliary valve E' must be first shifted to the position shown in Fig. 3, so as 90 to place the passages d² d³ in communication. The pressure of water received through the inlet-pipe d, by acting on the left-hand side of the valve-piston D', will force the several pistons D' D² D⁵ toward the right hand by a 95 force corresponding to the differences in area between the pistons D' D⁵. The space between the pistons D' D² is meanwhile open to the exhaust-passage c', and the water or fluid which is on the right hand of the piston D² will, by 100 the movement of that piston in the direction of the arrow shown in Fig. 3, be simply transferred through the passages d² d³, and will escape through the exhaust-passage c'.

If it be desired to stop the movement of the 110 piston C', the auxiliary valve E' will be shifted to the position shown in Fig. 2, and the water entering through the passage d² to the main valve-cylinder D, and acting on the right-hand side of the piston D², will move the main valve 115 and controlling-pistons D' D² D⁵ in the direction of the arrow shown in Fig. 2 by a pressure corresponding to the area of the smaller piston, D⁵, inasmuch as the pressure on that smaller piston is also toward the left hand, 120 and the pressure upon the two pistons D' D² is balanced. During the movement of the valve-piston D' toward the left hand from the position shown in Fig. 3 to the position shown in Fig. 2 it will momentarily cover the port c, 125 and the main operating-piston C' will momentarily stop, thus stopping the car A. If at the instant of stoppage the auxiliary valve E' be shifted to the position shown in Fig. 1, the valve-piston D' will remain over the port c 130 and the whole machine will be stopped; but if, instead of shifting the auxiliary valve E' from the position shown in Fig. 2 to the position shown in Fig. 1 at the instant the car

stops, said valve E' be allowed to remain in the position shown in Fig. 2, the main valve D' will continue to move toward the left hand of Fig. 2 until it arrives at the position therein shown. In such position the supply and exhaust passages c c' are in communication between the pistons D' D², thus permitting the main operating-piston C' to move toward the right hand of Fig. 1 and producing the descent of the car. It will therefore be seen that in order to stop the car, whether moving upward or downward, the auxiliary valve E' must be moved to its neutral or central position (shown in Fig. 1) at the moment when the main-valve piston D' closes the port c and produces a momentary stoppage of the piston C' and the car A. The passages d² d³ may be provided with throttling devices or screws d⁴, inserted as shown in Fig. 4, to regulate their capacity.

The movement of the auxiliary valve E' in the manner described is produced by an electric motor, F, which is controlled in its operation by an electric circuit, including a switch or circuit closing device, H, arranged in the car A. The electric motor here shown is of very simple construction, and comprises an armature-lever, f, which is fulcrumed to a suitable support, f', and has an upwardly-projecting arm, f², with which the valve-operating rod e³ is connected. The armatures f³ are at opposite ends of the lever f, and below them are magnet-coils f⁴, supported on a suitable base, f⁵. The balancing devices here shown consist of springs f⁶, which are connected with the armature-lever f on opposite sides of its fulcrum. These springs should be of equal tension, and when either one of the magnet-coils f⁴ is energized the corresponding end of the lever f will be drawn down, but when the circuit is broken the springs f⁶, by their balancing effect, will move the lever f to the central position shown in the drawings, and through the rod e³ will move the auxiliary valve E' to its neutral or inoperative position. (Shown in Fig. 1.)

The circuit-closing device or switch H which I prefer to employ in the car is best illustrated in Figs. 6 and 7. As shown, it consists of a segmental frame, h, which may be of insulating material, secured to the side of the car A, and a lever or arm, h', fulcrumed at its upper end, h², and provided at its lower end with a handle, h³, whereby it may be swung to and fro in a vertical plane. At the lower portion of the frame h, and at considerable distance apart on each side of a central vertical line, are electric contacts h⁴, with which the lever or arm h' makes contact as it may be swung in one or other direction. Upon the frame h are shoulders or projections h⁵, which limit the movement of the lever, arm, or handle h'. I prefer to make this device of considerable size, the lever or arm h' having, for example, a length of one foot or more, so that it will form a substantial lever or handle, which the elevator-attendant may keep grasped

in his hand, and which he may operate similarly to the ordinary lever or handle employed to shift the controlling-valve through suitable positive mechanical connections. It is advantageous to have the contacts h⁴ at a considerable distance apart upon opposite sides of a central vertical line, because then the lever or handle will have to be swung a suitable distance to make contact with one or other of them, and consequently contact will not be produced by moving the lever or handle h' for some distance on each side of its central position, as would naturally be the case when it is grasped in the hand of the attendant. In other words, the lever or handle h' may have a considerable range of movement on each side of its vertical position without making contact with either of the pins or projections h⁴, and in order to make contact with one or other of them the lever must be moved to a distance which would only be reached by its intentional operation. It is also advantageous to have the arm, lever, or handle h' fulcrumed at its upper end and hanging downward, because then it cannot drop accidentally from its middle position into contact with either contact pin or projection h⁴. The frame h, which may be of insulating material, may also have hubs or projections h⁶, which extend through the side of the car A, as shown in Fig. 7, and in which the fulcrum-pin h² and the contacts h⁴ of the switch are mounted.

The two terminals of the magnet-coils f⁴ are connected by a wire, i, which contains a battery, i', with the fulcrum h² of the switch in the car, and the other terminals of said coils are connected by wires i² with the contacts h⁴ of the switch. These wires i i², properly insulated, may extend to a support, i³, at about midway of the height of the elevator-shaft B, and beyond that point and to the car. The several wires may be gathered in a single cable, I, which is attached to the car, and from the end of which the several wires i i² lead to the points h² h⁴.

In the position of parts shown in Fig. 1 the car and the main operating-piston C' are stationary. If it be desired to ascend, the lever or handle h' is swung over upon one contact h⁴, and, the circuit being closed through one of the magnet-coils f⁴, the valve E' will be moved to the position shown in Fig. 3, and the movement of the pistons D' D² D³ to the position shown in Fig. 3 will follow, thereby placing the inlet-pipe d in direct communication through the passage c with the main operating-cylinder C. If it be desired to descend instead of ascend, the lever or handle h' will be swung in the opposite direction, so as to make contact with the other pin h⁴, thereby closing the circuit through the other magnet-coil f⁴ and producing the movement of the auxiliary valve E' to the position shown in Fig. 2. The pistons D' D² D³ will then move to the position shown in Fig. 2, and the operating-cylinder C, through the passages c c', will be placed in free communication with the at-

mosphere, so as to permit the movement of the piston C' in a direction to lower the car A. It will be understood that when the valve E' is set to a position to produce the ascent or descent of the car, the car may be stopped by shifting the auxiliary valve over to its reverse position, and then at the moment the car stops, by reason of the piston D' covering the port or passage e, swinging the lever or handle h' to mid-position, (shown in Figs. 1 and 6,) the circuit thus being broken, the balancing-springs f' will instantly return the auxiliary valve E' to its neutral or inoperative position. (Shown in Fig. 1.)

In the example of my invention shown in Figs. 8, 9, and 10 I have illustrated a valve apparatus similar to that which forms the subject of my aforesaid patent, No. 314,720, and no extended description of that valve apparatus will be necessary. J designates a casing which contains the main valve and its controlling-pistons, and j is the valve-chest containing the auxiliary or pilot valve. The auxiliary valve-rod j' is connected by a lever, j'', and link j''' with the main-valve rod, and the lever j'' is connected by a link, j'', with a rocker-arm, j'', from which leads a rod, e''. I term the auxiliary valve in this example of my invention the "pilot-valve," because during the ordinary operation of the main valve and controlling-pistons the auxiliary valve is moved automatically and simultaneously through the lever j'', the point of connection s of the link j''' with said lever constituting a fulcrum on which the lever swings. When, however, it be desired to shift the auxiliary or pilot valve, the rocker-arm j'' is moved by a push or pull upon the rod e'', and the movement will be transmitted through the link j'' and lever j''' to the auxiliary or pilot valve, because it offers less resistance to the movement than does the main valve and its controlling pistons. The electric motor F shown in this example of my invention comprises two series of electric magnets or magnet-coils, k k', arranged on opposite sides of a rock-shaft, k'', and loosely mounted upon the rock-shaft are levers k'' k'', which carry at their outer ends the armatures for said magnet-coils. Fast upon the shaft k'' are toes or projections k'' k'', on which the armature-levers k'' k'' rest, and when any armature-lever is drawn down by the energizing of the corresponding magnet-coil k k', it will, through the toe k'' or k'', on which it is supported, impart a turning movement to the shaft k'', and through an arm, k'', on the shaft such movement will be transmitted through the rod e'' to the rocker-arm j'', for shifting the auxiliary valve. The toes k'' k'' are arranged spirally upon the shaft k'', and it will be understood that if any one of the armatures supported by the levers k'' k'', on one side or the other of the shaft k'', be drawn down, the slight movement of the shaft k'' thus produced will bring the next armature on the same side of the shaft k'' within working distance of its magnet, and by the energizing of the magnets

of either series in succession a turning movement of the shaft k'', sufficient to shift or move the valve in one direction or the other, will be produced. The circuit-closing device or switch H, arranged within the car A, differs somewhat from that before described. I have represented a metallic rod, K, as supported in suitable hangers, K', from which it is insulated, and this rod extends the full height of the elevator-shaft, one of said hangers being at the bottom and the other at the top of the shaft. The wires i, leading from one end of the magnet-coils k k' in the two series, are shown as gathered in a cable, L, which leads to the lower end of the rod or shaft K, and said wires are there connected with said rod or shaft. The several wires i'', leading from the other ends or terminals of the magnet-coils of the two series and which contain batteries i'', may be gathered together in two cables, L' L'', which are shown as hung or supported at L' at a point which is near the top of the elevator-shaft, and are thence carried to the car A. Within the car is a segmental plate or frame, m, above which is a horizontally-swinging lever or handle, m', which is free to slide upon and is in electric contact with the upright rod or shaft K. In the segmental frame or plate are arranged two series of contacts, n n', with which the wires i'', leading from the two series of magnets k k', are connected, the wires i'' leading from one series of magnets, k, being connected with the contacts n, and the wires i'' leading from the other series of magnets, k', being connected with the contacts n'. Upon the free end of the lever or handle m' is pivoted a disk, m'', which may have an insulated handle, m''', and which itself is in electric connection with the lever or handle m'. This disk m'' has a turning movement on the lever or handle, which is limited by the pin and slot s' s'', and which is sufficient to bring a downward projection or contact-point, s'', upon the disk m'' in line with either series of contacts n n'.

It will be obvious from the above description that when the handle m''' of the disk m'' is grasped in the hand and an attempt made to swing the lever m' in one or other direction, the first pressure or force will turn the disk m'' so as to bring its downward projection or contact-point s'' in line with the series of contacts n or n', and a further pressure or force upon the handle m'' will swing the lever m' in one or other direction, thereby making contact successively through the pin or projection s'' with the several contacts n or n' of one or the other series. Such swinging movement of the lever will therefore close the circuit through the magnets k k' of one or other series in succession, and by the turning of the shaft k'', which results from the aggregate movement of the several armature-levers k'' k'' of one or other series, the auxiliary valve will be shifted in one or other direction.

What I claim as my invention, and desire to secure by Letters Patent, is—

1. The combination, with an elevator-car and a valve apparatus for controlling its movements, and comprising a main valve, a motor-piston for operating the same, and an auxiliary valve for controlling the movements of said main valve and motor-piston, of an electric motor connected with the auxiliary valve for operating it, and an electric circuit including said motor and a circuit-closing device to be operated on the car, whereby the operation of the electric motor on the auxiliary valve may be controlled, substantially as herein described. 5
2. The combination, with an elevator-car and a valve apparatus for controlling its movements, and comprising a main valve, a motor-piston for operating the same, and a pilot-valve for controlling the movements of the said main valve and motor-piston, and connected with the main valve and motor-piston so as to move simultaneously therewith, of an electric motor connected with the pilot-valve for operating it, and an electric circuit including said motor and a circuit-closing device to be operated on the car, whereby the operation of the electric motor on the pilot-valve may be controlled, substantially as herein described. 10
3. The combination, with an elevator-car and valve apparatus for controlling its movements, and comprising a main valve, a motor-piston for operating the same, and an auxiliary valve for controlling the movements of said main valve and motor-piston, of an electric motor comprising an armature-lever connected with the auxiliary valve and electro-magnets for moving the said lever and valve in opposite directions, and an electric circuit including said electric motor and a circuit-closing device on the car, whereby the operation of the said motor-piston and valve may be controlled, substantially as herein described. 15
4. The combination, with an elevator-car and a valve apparatus for controlling its movements, and comprising a main valve, a motor-piston for operating it, and an auxiliary valve for controlling the movements of said main valve and motor-piston, of an electric motor for operating the auxiliary valve, an electric switch on the car, comprising a hanging arm or lever fulcrumed at its upper end and contacts, and an electric circuit including said electric motor and switch, substantially as herein described. 20
5. The combination, with an elevator-car and a valve apparatus, as described, for controlling its movements, and comprising a main valve and an auxiliary valve, of an electric motor comprising the armature-lever f , connected with the auxiliary valve, and the electro-magnets $f^1 f^2$, arranged on opposite sides of the fulcrum of said lever, and balancing devices for returning the armature-lever to central position after operation by either magnet, and an electric circuit including said motor and a circuit-closing device upon the car, and whereby the said electric motor and auxiliary valve may be controlled, substantially as herein set forth. 25
